UNITED STATES PATENT OFFICE.

ALBERT L. SILBERSTEIN, OF NEW YORK, N. Y.

DESIGN FOR A SCISSORS-CASE.

SPECIFICATION forming part of Design No. 24,274, dated May 7, 1895.

Application filed March 25, 1895. Serial No. 543,157. Term of patent 14 years.

To all whom it may concern:

Be it known that I, ALBERT L. SILBERSTEIN, a citizen of the United States, residing at New York city, in the county and State of New York, have invented and produced a new and original Design for a Scissors-Case, of which the following is a specification, reference being had to the accompanying drawing, forming part thereof, in which the figure is a perspective view of a scissors-case, showing my design.

The leading feature of my design consists in a sheath A, terminating at its upper end in the widened head portion B.

I claim—

The design for a scissors case, substantially as shown and described.

ALBERT L. SILBERSTEIN.
